(57) **CLAIM**

The ornamental design for a faucet, as shown and described.

DESCRIPTION

FIG. 1 is a front view of a faucet, showing my new design.

FIG. 2 is a rear view thereof.

FIG. 3 is a left side view thereof.

FIG. 4 is a right side view thereof.

FIG. 5 is a top view thereof.

FIG. 6 is a bottom view thereof.

FIG. 7 is a front perspective view thereof.

FIG. 8 is a rear perspective view thereof; and,

FIG. 9 is a perspective view thereof, shown in an in-use condition.

The broken lines in the drawings depict portions of the faucet that form no part of the claimed design.

1 Claim, 9 Drawing Sheets
